UNITED STATES PATENT OFFICE.

HARRY L. ATKINSON, OF SAN FRANCISCO, CALIFORNIA.

FOLLOWER-BLOCK MOUNTING.

Application filed March 14, 1923. Serial No. 624,949.

To all whom it may concern:

Be it known that I, HARRY L. ATKINSON, a citizen of the United States, residing at the city and county of San Francisco and 5 State of California, have invented new and useful Improvements in Follower-Block Mountings, of which the following is a specification.

This invention relates to filing cabinets 10 such as are employed for filing data bearing sheets or reference cards. Devices of this character usually embody a file drawer which forms a part of the cabinet and which is pulled out to expose and permit access to 15 the sheets or cards contained therein. As the quantity of these sheets or cards generally increases and diminishes from time to time it is customary to provide a follower movable longitudinally of the file drawer 20 which can be adjusted to any position therein to maintain the sheets or cards on edge that they may be easily selected and referred to.

Prior to my invention devices for this purpose, especially in the larger size file drawers, 25 have not proven entirely satisfactory as they easily become out of order and do not firmly hold a quantity of sheets or cards in proper position.

Therefore, it is the principal object of the present invention to provide a generally improved and simplified mounting for followers of filing cabinet drawers which will be efficient in operation and which will 30 permit the follower to be expeditiously adjusted longitudinally of the drawer and be firmly secured in any desired position.

In carrying out this object, I provide a file cabinet drawer with a guideway formed 40 longitudinally along its bottom. A pair of guide members are mounted in this guideway and connected with the bottom of the follower by a link mechanism whereby when the follower is raised, its position may be 45 adjusted longitudinally along the guideway and when the follower is released, its weight automatically extends the guide members to frictionally engage the sides of the guideway and firmly hold the follower in position.

One form which the invention may assume is exemplified in the following description and illustrated by way of example in the accompanying drawings, in which:—

Fig. 1 is a fragmentary view in vertical section of a file cabinet drawer and follower

with the preferred form of my invention applied thereto, with the follower mounting disclosed as firmly holding the follower in place.

Fig. 2 is a similar view disclosing the mounting in a position permitting the follower to be moved longitudinally of the drawer.

Fig. 3 is a perspective view of the mounting disclosing its construction.

Fig. 4 is a perspective view of one of the guide members.

Referring more particularly to the accompanying drawings, 10 indicates a filing cabinet drawer of suitable proportions and equipped with the usual follower plate 11. The bottom of the drawer is longitudinally slotted as at 12 and fitted with a channeled member 14. This member is somewhat 70 wider than the slot 12 and is secured to the bottom of the drawer in alignment with the slot. The portions of the bottom of the drawer at the sides of the slot overhang the sides of channeled member as at 15 80 thereby forming a guideway 16.

Mounted in the guideway is a pair of guide members 16^a comprising longitudinal guide rails 17 and transverse lugs 18. The latter project inwardly toward each other as shown 85 in Figs. 1 and 2. The lugs 18 are pivotally connected to links 19 which in turn pivotally connect with a frame bar 20. The top of this bar is rigidly connected to the bottom flange 21 of the follower plate 11. 90

The links 19 are of such a length that when the follower is in engagement with the bottom of the drawer, the rails 17 of the guide members frictionally engage the sides of the guideway and firmly clamp the follower in 95 position. However, as the rails cannot be moved vertically, due to the formation of the guideway, when the follower is raised, the links 19 act to draw the guide rails toward each other and discontinue the frictional engagement between them and the sides of the guideway. The follower may then be adjusted longitudinally of the drawer and thereafter clamped in place by merely releasing it. The weight of the 105 follower spreads the guide members and forces them into frictional engagement with the sides of the guideway.

As the guide rails 17 are quite long and as there is a firm connection between them 110 and the follower, the latter will be firmly held in a set position. In this position, the

mechanism is locked and, as the thrust of the contents is lengthwise of the drawer and that of the locking device is crosswise, the follower cannot be dislodged by the contents when the drawer is opened and closed.

In operation, if it is desired to adjust the position of the follower, it is raised to release the engagement of the mounting with the guideway and then moved longitudinally of the drawer to the desired position. The follower is then released, its weight automatically causing the rails 17 to spread and forcing them into frictional engagement with the sides of the guideway to clamp the follower in position.

From the foregoing it is obvious that a very simple and inexpensive follower mounting is provided which will be positive in operation and which will not easily become out of order.

While I have shown the preferred form of my invention, it is to be understood that various changes in its construction may be made without departing from the spirit of the invention as defined in the appended claims.

Having thus described my invention, what I claim and desire to secure by Letters Patent is:—

30 1. In combination with a filing receptacle, a follower mounted therein, a guideway in the bottom of the receptacle, a follower mounting in said guideway and connected to the follower, said mounting operable by 35 vertical movement of the follower to clamp the follower to the bottom of the receptacle or release it to permit it to be longitudinally adjusted therein.

2. In combination with a filing receptacle

having a follower therein, a guideway 40 formed longitudinally along the bottom of the receptacle, an expansible follower mounting in said guideway and connected to the follower, said mounting operable by vertical movement of the follower to expand 45 and engage the sides of the guideway to clamp the follower in position or to contract to permit the follower to be longitudinally adjusted in the receptacle.

3. In combination with a filing receptacle having a follower therein, a guideway in the bottom of said receptacle, a pair of guide members therein, a link connection between said members and the follower whereby vertical movement of the follower 50 will affect the position of said members relative to the sides of the guideway for the purpose described.

4. In combination with a filing receptacle having a follower therein, a guideway 60 in the bottom of said receptacle parallel to the line of travel of the follower, a pair of guide members in said guideway positioned one adjacent to each side thereof, a link connection between the said members and the follower whereby vertical movement of the latter will affect the relative positions 65 of the guide members, said guideway being formed to prevent vertical movement of said guide members whereby downward 70 movement of the follower will spread the guide members and cause them to engage the sides of the guideway and clamp the follower in position and upward movement of the follower draw said guide members toward each other to release the follower to 75 permit it to be adjusted in the receptacle.

HARRY L. ATKINSON.
